US00D445670S

(12) **United States Design Patent**
De Baschmakoff

(10) Patent No.: **US D445,670 S**
(45) Date of Patent: ** Jul. 31, 2001

(54) **BOTTLE WITH SPRAY ACTUATOR CAP**

D. 404,294 * 1/1999 Baschmakoff D9/300
D. 404,305 * 1/1999 Baschmakoff ..... D9/443 X

(75) Inventor: **Thierry De Baschmakoff, Paris (FR)**

* cited by examiner

(73) Assignee: **Conopco, Inc., New York, NY (US)**

Primary Examiner—Cathron C. Brooks

(**) Term: **14 Years**

(74) Attorney, Agent, or Firm—Milton L. Honig

(21) Appl. No.: **29/131,481**

(57) **CLAIM**

(22) Filed: **Oct. 23, 2000**

The ornamental design for a bottle with spray actuator cap, as shown and described.

(51) LOC (7) Cl. **09-01**

DESCRIPTION

(52) U.S. Cl. **D9/300**

FIG. 1 is a perspective view from the right side showing my new design;

(58) Field of Search D9/300, 436, 448,

FIG. 2 is a right side elevational view;

D9/449, 450, 503, 544, 545; 222/153.01,

153.11, 153.12, 153.13, 153.14, 321.7,

321.8, 321.9, 402.1, 402.21, 402.24

FIG. 3 is a front elevational view;

FIG. 4 is a rear elevational view;

FIG. 5 is a left side elevational view;

FIG. 6 is a top plan view; and,

FIG. 7 is a bottom plan view.
